UNITED STATES PATENT OFFICE.

ALBERT WILSON, OF YUMA, ARIZONA.

KEYLESS PADLOCK.

Application filed July 1, 1924. Serial No. 723,553.

To all whom it may concern:

Be it known that I, ALBERT WILSON, a citizen of the United States, residing at Yuma, in the county of Yuma and State of Arizona, have invented certain new and useful Improvements in Keyless Padlocks, of which the following is a specification.

This invention appertains to locks and the primary object of the invention is to provide a permutation padlock of novel and simplified construction, whereby the necessity for utilizing a key with the padlock will be entirely eliminated.

A further object of the invention is the provision of a novel permutation padlock embodying a barrel and rigid end plates, and novel means for forming the barrel and associating the combination rings with the barrel.

20 A further object of the invention is the provision of novel means for associating one of the end plates of the barrel therewith, whereby accidental turning movement of said end plate relative to the barrel is precluded.

25 A further object of the invention is to generally simplify the construction of permutation padlocks and render the same durable and efficient in use.

30 With these and other objects in view, the invention consists in the novel construction, arrangement and formation of parts, as will be hereinafter more specifically described, claimed and illustrated in the accompanying drawings, in which drawings:

Figure 1 is a perspective view of the padlock showing the various parts thereof in disassembled positions,

Figure 2 is a longitudinal section through the improved padlock in its assembled position and the shackle of the lock in place,

Figure 3 is a fragmentary longitudinal sectional view taken at right angles to Figure 2 showing the means carried by the combination rings for engaging the arms of the shackle of the padlock,

Figure 4 is a top plan view of the improved padlock with the cover or end plate removed and the arms on the shackle in cross section, and

Figure 5 is a detailed elevation of the shackle.

Referring to the drawings in detail, wherein similar reference characters designate corresponding parts throughout the several views, the letter A generally indi-

cates the improved padlock which comprising an axially disposed solid cylindrical barrel 10 having formed integrally therewith or rigidly connected thereto a lower end plate 11, the periphery of which extends beyond the outer face of the barrel forming a stop, for a purpose, which will be herein-after more fully described. The solid barrel 10 at opposite diametric points is provided with longitudinally extending semi-cylindrical grooves 12, for a purpose, which will be also hereinafter more fully described. At right angles to the grooves 12 the opposite sides of the barrel 10 I have provided 70 with equi-distantly spaced retaining lugs 13 which act as means for normally holding the combination rings 14 in place on the barrel as will be hereinafter more clearly described, as the description proceeds. The upper end 75 of the barrel 10 receives the cover or top plate 14' and this plate is of such a size as to project beyond the outer surface of the barrel. The lower face of the cover or top plate 14' at the periphery thereof is provided with a depending flange 15 for receiving the upper end of the barrel. The cover or top plate 14' is held in place against displacement in any desired way, and as shown in the drawings I have provided an 80 axially disposed retaining screw 16 which extends through the cover or top plate 14' into the barrel. The inner face of the cover or top plate 14' is provided with an opening at a point spaced of the axial center thereof for receiving a pin 17 carried by the upper end of the barrel and it is obvious that when the cover plate is in position and the pin is fitted within the opening that rotation of the cover or top plate on the barrel 85 is prevented.

The spaces between the lugs 13 formed on the outer surface of the barrel form guide ways 18. The combination rings 14 are of course of annular construction and 100 are disposed on the barrel in abutting relation to one another and are held in place against displacement by the plates 11 and 14'. The inner faces of each of the combination rings 14 are provided with spaced 105 ribs 19 of substantially semi-circular configuration and these ribs are disposed intermediate the upper and lower faces of the rings. The spaces between the ribs 19 of each ring are of substantially the same size 110 as the retaining lugs 13 which permits the rings to be initially placed on the barrel.

The ribs 19 are adapted to fit within the guide ways 18 between the lugs 13. The outer face of each combination ring is provided with grooves 20 which are equi-distantly spaced and these grooves are numbered to facilitate the working of the combination. The outer surface of the cap or top plate 14 can also be grooved and provided with numbers so as to facilitate the working of the combination.

The shackle 21 of the padlock is provided with parallel arms 22 the outer ends of which are reduced in cross section as at 23 and provided with spaced locking notches 24. The spaces between the terminals of the semi-circular ribs 19 are also of such size to receive the reduced portions 23 of the parallel arms therebetween.

The device is assembled by placing the combination rings upon the barrel 10 after which the cover or top plate 14' is secured in place. The lock is now ready for use. The combination of the lock is of course determined by the position of the numbers on the outer face of the rings relative to the spaces between the terminals of the ribs 19 and when each padlock is sold the combination for that particular lock is given therewith.

In operation of the improved lock the rings are so placed that the spaces between the locking ribs will lie in registration with the semi-cylindrical notches or slots 12 which will form cylindrical ways for receiving the reduced arm 23 of the shackle 21. The shackle is now placed in position and the rings are turned indiscriminately and the ribs 19 will ride into the notches 24 in the reduced extensions of the shackle arms thereby holding the shackle against movement and displacement. When it is desired to remove the shackle it is merely necessary to again align the spaces between the terminals of the ribs 19 with the longitudinal notches or slots 12 and the shackle can be easily pulled out from the barrel. Owing to the position of the ribs 19, it can be seen that the same can easily engage between the lugs 13 in the ways 18 and in the notches 24.

It is to be also noted that when the top plate 14' is removed that the rings also can be removed by aligning the spaces between the terminals of the ribs with the lugs 13.

There can be as many of the rings as desired, that is, the padlock can be made in different sizes and as shown in the drawings I have provided four of the locking combination rings.

One of the main features of the padlock is the large number of different combinations, which can be set up and that the padlock can be easily sold in a knocked down condition. In fact it is primarily intended to sell the lock in a knocked down condition and permit the buyer to assemble the same and set up any combination that is desired.

Changes in details may be made without departing from the spirit or the scope of this invention, but:—

What I claim as new is:

The combination padlock comprising a solid cylindrical barrel, having longitudinal grooves therein at diametrically opposite points, equi-distantly spaced longitudinally aligned lugs formed on the barrel intermediate the grooves, locking rings rotatably received in the barrel, spaced semicircular ribs formed on the inner faces of the locking rings, a shackle having parallel arms formed with equi-distantly spaced notches, the ribs of the rings being adapted to engage in the notches and with the longitudinally aligned lugs, a cap plate fitted in one end of the barrel to hold the locking rings in place, the inner face of the cap plate having formed therein a centrally disposed opening, a pin carried by the barrel and arranged in the opening and serving to hold the cap plate against rotation, and a threaded element passing through the cap plate and engaging the barrel whereby to hold the upper end of the latter against the cap plate and thus cause the ribs to contact with the lugs with sufficient friction as to hold the rings against accidental rotation.

In testimony whereof I affix my signature.
ALBERT WILSON.
